UNITED STATES PATENT OFFICE

OLIVER H. TAYLOR, OF BROOKLYN, NEW YORK.

STEAM-GENERATOR.

SPECIFICATION forming part of Letters Patent No. 463,652, dated November 24, 1891.

Application filed April 23, 1891. Serial No. 390,141. (No model.)

To all whom it may concern:

Be it known that I, OLIVER H. TAYLOR, of Brooklyn, in the county of Kings and State of New York, have invented a new and useful 5 Improvement in Steam-Generators, of which the following is a specification.

My invention relates to an improvement in steam-generators of the water-tube type, in which provision is made for free expansion 10 and contraction of the several banks of tubes without any liability of straining or rupturing any of the parts, and in which the products of combustion are caused to come into intimate contact with the several water-tubes 15 and remain for an extended period of time in such intimate contact during their passage from the fire-chamber to the uptake.

A practical embodiment of my invention is represented in the accompanying drawings, 20 in which—

Figure 1 is a view in side elevation, partly in section, the side wall of the furnace being removed to show the arrangement of tubes within. Fig. 2 is a transverse vertical section taken on a plane represented by line xx of Fig. 1. Fig. 3 is a horizontal section through line yy of Fig. 1. Fig. 4 is a top plan view, the top or ceiling of the furnace being removed; and Fig. 5 is an enlarged view in detail of one of the cap-screws.

A A represent the side walls of the furnace and A' its top or ceiling. A set of grate-bars is represented at a , extending from the front back to a bridge-wall a' , and at the front above the grate-bars the furnace is provided with a door a^2 , through which the coal is supplied to the grate. Water columns B and B' are located at the diagonally-opposite corners of the furnace, and from each there extends 40 a vertical series of horizontal headers, those extending from the column B being denoted by b and those extending from the column B' being denoted by b' . The headers b and b' connect with the columns at one end only by 45 means of suitable connecting-tubes b^2 , their opposite ends being supported in the furnace-wall in such a manner as to leave the headers free to expand or contract longitudinally without straining either the wall or the column 50 with which they are connected.

From each of the headers b and b' there extends a bank of tubes across or partially

across the space within the furnace. In the form which I have chosen to represent my present invention I have shown certain banks 55 of tubes extending in opposite directions from two opposite headers and so arranged that those from one header will alternate with those from the opposite header, and I have represented certain other banks of tubes as extending in 60 opposite directions from the headers located in different vertical planes, the bank from each header forming a closed horizontal wall throughout the length of the tubes. In each instance the bank of tubes from a header 65 stop short of the opposite wall of the furnace and are closed at their ends farthest from the header, so that they are free to expand from the header to which they are attached without producing any strain upon any part of 70 the furnace. In the accompanying drawings those banks of tubes which extend in opposite directions from headers in substantially the same plane and alternately interlock are represented by C and C', those from one half 75 being represented by C and those from the opposite half by C'. Those banks of tubes which are placed side by side in proximity to each other and form a substantially horizontal closed wall from headers lying in different 80 horizontal planes are represented by D and D'. I have here shown the tubes D and D' as of greater diameter than the tubes C C', and have located the former at the upper portion 85 of the furnace for the most part above the normal water-line, the intention being to utilize them to a considerable extent as means for superheating the steam.

In speaking of the banks of tubes as extending from their headers in substantially horizontal planes I wish to be understood that while they might be so arranged my preference is that they shall have a slight inclination from the point where they are connected to the headers upwardly toward their free 95 ends. This inclination is shown as considerably exaggerated in Fig. 1, the intention being that their slant shall not be sufficient to carry the lower side of their free end quite up to the upper side of their end at the header. 100

The banks of tubes C C' are of different lengths, the bank C extending nearly across the entire inner space of the furnace, leaving only sufficient room between their free

ends and the furnace-wall to allow for any longitudinal expansion to which they may be subjected, while the banks C' stop sufficiently short of the opposite wall to form between 5 their free ends and the wall a flue for the products of combustion which escape from the fire-chamber above the grate a. As the banks C and C' emanate alternately from the rear and front of the furnace, it follows that the 10 flues for the escape of the products of combustion will be alternately in proximity to the rear and front of the furnace, so that these products will be caused to flow back and forth beneath the horizontal walls of tubes in intimate 15 contact with the tubes, thereby exposing them to the full effect of the heat.

Where the banks of tubes are arranged as indicated by C and C', they may be expanded into their headers, provision for so connecting them being made by hand-holes c in the sides of the headers opposite the ends of the tubes. Where the tubes are arranged closely side by side, as in the case of the banks D D', it will be necessary to connect them by suitable 25 necks c'. The neck which I have provided for this purpose comprises a hollow cap-screw, the body e of which is screw-threaded on its exterior to engage a corresponding screw-thread in the end of the tube, while its 30 flanged head E is adapted to engage the end of the tube when it is screwed home within the end of the tube. The bore e' through the cap-screw is also provided with a screw-thread adapted to receive one of the screw-threaded 35 ends of the neck or nipple c', the opposite end of said nipple being screw-threaded and adapted to engage a screw-threaded opening in the side of the header. The free ends of the several tubes are closed by cap-screws 40 quite similar to those just described, with the exception that their heads E' are solid instead of being provided with a screw-threaded bore for the reception of a neck or nipple. The ends of the tubes are beveled, as shown 45 at e², Fig. 5, to engage the beveled inner sides e³ of the rims E', so as to force a tight joint as the cap is screwed home. The bevel on the water-tube has a slant from the exterior downwardly and outwardly toward the end 50 of the tube and the bevel on the screw-cap being downwardly and inwardly toward the head of the cap. By this arrangement the tendency of the end of the tube to spread apart, either by the insertion of the screw-cap or by force of steam, is entirely obviated 55 and a tight joint effected. The several banks of tubes are supported in the desired position by means of cross-bars F, which rest at their opposite ends in the furnace-walls.

60 The side walls of the fire-chamber are formed by vertical banks of tubes, those represented by G and located upon one side of the fire-chamber emanating from the column B' and those represented by G' upon the opposite side of the fire-chamber emanating from the column B. These tubes G and G', like those of the several banks before referred

to, have their free end closed and separated a short distance from the furnace-wall, so as to admit of any longitudinal expansion which 70 may take place. These tubes G and G' are also preferably set at a slight upward inclination. The columns B and B' connect at their upper ends through pipes H and H' with a centrally-located steam-dome I, from which 75 the steam may be conducted away for use. The lower portions of the columns B and B' communicate with a mud-drum K through suitable connecting-pipes k and k'.

Instead of arranging the banks of tubes, 80 some in the form of C C' and others in the form of D D', I may arrange the entire set within the furnace all of one form or of the other.

What I claim is—

1. In a steam-generator, the combination, with water-circulating headers at the opposite walls of the furnace, of banks of tubes emanating alternately from the headers at the opposite walls, their free ends being spaced 90 from any obstruction, so as to admit of the free expansion and contraction of the tubes, the bank of tubes from one header being shorter than the bank of tubes from the opposite header, whereby a flue is formed between the free ends of first-mentioned bank 95 of tubes and the wall, substantially as set forth.

2. In a steam-generator, the combination, with headers located in vertical series, of 100 banks of tubes emanating alternately from the headers of two opposite series and extending toward one another and alternately interlocking to form a horizontal wall over a portion of the interior of the furnace, the free 105 ends of the several banks of tubes being spaced from any obstruction, the free ends of one bank being stopped short of the points of emanation of an opposite corresponding bank to form a flue for the products of combustion, substantially as set forth.

3. In a steam-generator, the combination, with vertical series of headers, of banks of tubes emanating from corresponding opposite 115 headers of the series and being unobstructed 120 at their free ends to expand and contract, the said banks being arranged to alternately interlock to form a horizontal wall across the space within the furnace, and other banks of tubes emanating from opposite headers and arranged side by side, their free ends being spaced from any obstruction to allow free expansion and contraction and also to form a flue for the products of combustion, substantially as set forth.

4. In a steam-generator, the combination, with water columns at the opposite ends of the furnace, and vertical series of headers extending laterally and emanating from the respective water columns, the ends of the headers being spaced from any obstruction to admit of free expansion and contraction, of 130 banks of tubes extending in opposite directions from corresponding opposite headers

along the interior of the furnace, the ends of the banks of tubes being spaced from any obstruction to admit of free expansion and to form flues for the products of combustion, 5 substantially as set forth.

5. The combination, with the vertical series of headers, of banks of tubes extending from corresponding headers in the different series toward one another, one bank of each series 10 forming a closed wall with the corresponding bank from the opposite header from one wall of the furnace to within a short distance of the opposite wall, the said banks of tubes having a slight inclination upward from the 15 points from which they emanate, the said banks of tubes being closed at their free ends and stopped short of any obstruction to allow of free expansion and contraction, substantially as set forth.
- 20 6. The combination, with the water-tube provided with a beveled end, the bevel having a slant from the exterior downwardly and outwardly toward the end of the tube, of a screw-cap having a flange provided with a 25 beveled inner face, the bevel being down-

wardly and inwardly toward the head of the cap, the bevel on the cap adapted to engage the beveled end of the tube when the cap is screwed home to force a tight joint, substantially as set forth.

7. The herein-described generator, comprising the water columns at its opposite ends, vertical banks of water-tubes emanating, respectively, from the water columns at the opposite ends of the furnace and forming the 30 side walls of the fire-chamber, headers extending laterally in vertical series from the water columns, horizontal banks of tubes emanating from the headers and extending toward one another across the interior of the furnace, 35 forming horizontal walls, the said banks being spaced at their free ends from the opposite walls of the furnace to form flues for the products of combustion and a suitable steam-dome in connection with the columns, substantially as set forth.
